Primary Examiner — Anhdao Doan(74) *Attorney, Agent, or Firm* — Andrus Intellectual Property Law, LLP(57) **CLAIM**

The ornamental design for a hearing aid component cap, as shown and described.

DESCRIPTION

FIG. 1 FIG. 1 is a top perspective view of a hearing aid component cap according to my new design; FIG. 2 is a front elevation view thereof;

FIG. 3 is a rear elevation view thereof;

FIG. 4 is a side elevation view thereof, the opposite side elevation view being identical thereto;

FIG. 5 is a top plan view thereof; and,

FIG. 6 is a bottom plan view thereof.

The broken lines in the FIGS. 1-6 illustrate portions of the hearing aid component cap that form no part of the claimed design. The dash-dot lines in FIGS. 1-5 between the solid line portions and the broken line portions of the hearing aid component cap depict the boundaries of the claimed design and form no part of the claimed design.
